[57] **CLAIM**

The ornamental design for a cabinet for electronic data processing equipment, as shown and described.

DESCRIPTION

FIG. 1 is a top, front and side perspective view of a cabinet for electronic data processing equipment showing our new design;

FIG. 2 is a top plan view thereof;

FIG. 3 is a top, front and side perspective view of a second embodiment thereof;

FIG. 4 is a top, rear and opposite side perspective view thereof; and,

FIG. 5 is a top plan view thereof.

The undisclosed rear and side views of the first embodiment are identical in appearance to those of the second embodiment, the only different being the number of cabinets.

FIG. 1

FIG. 2

FIG. 3

FIG. 4

FIG. 5
